SAFETY RAZOR

Giuseppe F. Pinsuti, New York, N. Y.

Application November 12, 1946, Serial No. 709,375

5 Claims. (Cl. 30—74.1)

1

This invention relates to improvements in razors and particularly to razors of the safety type in which a relatively thin blade is carried by a blade-supporting member.

When using the safety razors now being marketed it is appreciated that, while shaving, the razor becomes clogged with lather along the cutting edges of the blade, so that after one or more strokes the razor will pull or scrape rather than cut, which is highly undesirable.

Therefore, one object of the present invention is the provision of a device of the character described which allows a cleaning of the blade supporting members as well as a sharpening of the razor blade without taking the razor apart and without removing the razor blade from the position in which it is while shaving.

Another object of the present invention is the provision of a device of the character described which is particularly well adapted for sharpening and honing the razor blade, without removing it from the razor, by means of a sharpening and honing device of the type described in my co-pending patent application which is filed together with the present application.

Still another object of the present invention is the provision of a device of the character described which has a top member or retainer cap whose upper surface is shaped in such a manner as to afford a very convenient guide to facilitate the sharpening of the razor blade without removing it from its position.

Yet still a further object of the present invention is the provision of a device of the character described which is light in weight, handy in use, and simple in construction so that it can be manufactured and sold at a very reasonable price, but which is sturdy, durable, and well adapted to withstand the rough usage to which devices of this type are frequently subjected.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings the preferred forms of the invention have been shown.

In said drawings:

Figure 1 is a top plan view of a preferred embodiment of my invention;

Figure 2 is a side elevation of the same;

2

Figure 3 is a front elevation of the same;

Figure 4 is a sectional view on the line 4—4 of Figure 1;

Figure 5 is a sectional view on the line 5—5 of Figure 2;

Figure 6 is a plan view of a blank used for a detail; and

Figure 7 is a plan view of a modified blank used for a detail.

10 Similar reference characters refer to similar parts throughout the several views.

In the drawing the numeral 1 denotes an entire safety razor constructed in accordance with my invention. It has a customary handle 15 into whose upper portion is extended an internally threaded bore 3 adapted to have an externally threaded pin 4 screwed thereinto. The pin 4 is extended from the lower side of a top member or retainer cap 5 which has thin longitudinal side portions and a thick upwardly bulged center portion, and whose lower side is preferably provided with a longitudinal, narrow rib 6 that extends at both sides of the pin 4 toward the end portions of the retainer cap 5 and is adapted to be extended through the longitudinal slot which is normally provided in the longitudinal center of a razor blade 15.

The blade supporting member, which is adapted for supporting a razor blade 15 from below and which is normally in the hitherto known safety razors consists of one single piece, according to my invention consists of three pieces, namely a longitudinal narrow center bar 7 and a pair of supporting members 11 and 12 which are movably attached to the center bar 7. The upper side of the center bar 7 preferably is provided with a longitudinal groove 8 adapted to receive the lower portion of the rib 6 when the part 5 is screwed upon the part 7 with a razor blade 15 interposed between the parts 5 and 7. The lower side of the center bar 7 is provided with a recess 9 adapted to receive the upper extremity of the handle 2 (Figure 4), and this recessed portion 9 is perforated so that the pin 4 can loosely be extended therethrough.

The end portions 10 of the center bar 7 preferably are reduced and cylindrical and are extended through the lug-shaped lateral portions of the supporting members 11 and 12, so that the latter can be moved on the part 7 and can be either in a substantially horizontal position (which I call the "shaving position") as shown in full lines in Figures 3 and 5, or in a substantially vertical position (which I call the "cleaning and sharpening position") as indicated in

dash-and-dotted lines in Figure 3. If the supporting members are in the last mentioned position, the edge portions of the razor blade 15 are at both sides unobstructed, so that they can be sharpened and honed, thereby the raised center portion of the upper side of the part 5 constituting a guide for moving the sharpening or honing device along the cutting edges of the blade 15; likewise, in this last mentioned position the members 11 and 12 themselves can be cleaned easily and any lather, hair and the like can be removed therefrom easily and quickly without taking the razor 1 apart and without removing the blade 15 therefrom.

In order to keep the supporting members 11 and 12 safely in the shaving position, I prefer to provide them with suitable locking means. I prefer to carry out this feature of my invention in the manner shown in the drawing, where it will be seen that tongue portions 13, which have semi-circular recesses 14 on their extremities, are provided on the members 11 and 12 and are inwardly extended toward the pin 4. When the members 11 and 12 are in the shaving position, the extremities of the tongue portions 13 are between the lower side of the razor blade 15 and the upper side of the center bar 7, and when then the handle 2 is screwed tightly upon the pin 4, said extremities are locked firmly between the parts 7 and 15, so that the members 11 and 12 are kept safely in the shaving position, thus constituting reliable guards which prevent a cutting of the face by the blade 15.

In order to move the supporting members 11 and 12 from the shaving position into the cleaning and sharpening position, all that is necessary is to loosen the handle 2, so that it is no longer tightly screwed upon the pin 4 but that it still loosely engages the same, whereupon there will be sufficient space between the parts 7 and 15 and 5 respectively to swing the members 11 and 12 about ninety degrees downward around the hinging portions 10.

In order to reduce the cost of my new and improved safety razor, I prefer to make the members 11 and 12 of blanks. In Figure 6 such a substantially E-shaped blank is shown consisting of a main portion 16, a tongue portion 17 and side portions 12a which only have to be bent at right angles relative to the main portion 16 in order to make them ready for assembly. In Figure 7 a slightly modified substantially U-shaped blank is shown which has a pair of tongue portions 19 extending from the main portion 18 adjacent the lug portions 11a.

Since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having thus fully described my said invention, what I claim as new and desire to secure by Letters Patent is:

1. In a safety razor, the combination of a retainer cap having thin longitudinal side portions and a thick center portion from whose lower side extends a pin adapted to be screwed into the up-

per extremity of a handle, with a longitudinal center bar having an aperture through which said pin is loosely extended, and a guard plate being longitudinally divided into two members 5 which are hinged to the extremities of said center bar and provided with inwardly extended tongues adapted to be pressed between said center bar and a razor blade which is inserted beneath said retainer cap, so as to keep said members in a substantially horizontal position when said handle is screwed tightly upon said pin, but to allow said members to be brought into a substantially vertical position when said handle is loosened on said pin thus rendering both surfaces 10 of the edge portions of said razor blade unobstructed for sharpening the blade without taking it off from the razor.

2. A safety razor comprising a retainer cap having thin longitudinal side portions and a thick upwardly bulged center portion from whose lower side extends a threaded pin, a handle having a threaded axially into its upper portion extended bore adapted to engage said pin, a longitudinal narrow center bar through whose perforated 25 middle portion said pin is loosely extended, and a guard plate being longitudinally divided into two supporting members which are hinged to the extremities of said center bar and provided with inwardly extended tongues adapted to have their 30 extremities pressed between the upper side of said center bar and a razor blade which is inserted beneath said retainer cap, so as to keep said members in a substantially horizontal position when said handle is screwed tightly upon 35 said pin, but to allow said members to be brought into a substantially vertical position when said handle is loosened on said pin thus rendering the surfaces of the razor blade and said supporting 40 members accessible for removing the matter accumulated thereon while shaving.

3. A safety razor comprising a retainer cap having thin longitudinal side portions and a thick upwardly bulged center portion from whose lower side extends a threaded pin, a handle having a threaded axially into its upper portion extended bore adapted to engage said pin, a longitudinal narrow center bar having reduced cylindrical end 45 portions and a perforated middle portion through which said pin is loosely extended, and a guard plate being longitudinally divided into two supporting members which have lug-shaped side portions that hingedly engage the cylindrical end 50 portions of said center bar and which are provided with inwardly extended tongues adapted to have their extremities pressed between the upper side of said center bar and a razor blade which is inserted beneath said retainer cap, so as to keep said members in a substantially horizontal position when said handle is screwed tightly upon 55 said pin, but to allow said members to be brought into a substantially vertical position when said handle is loosened on said pin thus rendering both surfaces of the edge portions of the razor blade accessible without removing it from its position, thereby said upwardly bulged center portion of 60 said retainer cap serving as a guide to facilitate the sharpening of the blade.

4. In a safety razor, the combination of a retainer cap from whose lower side extends a pin adapted to be screwed into the upper extremity of a handle, with a longitudinal center bar having an aperture through which said pin is loosely extended, and two guard members hinged to the extremities of said center bar and provided with inwardly extended tongues adapted to be pressed

5

between said center bar and a razor blade which is inserted beneath said retainer cap so as to keep said members in a substantially horizontal position when said handle is screwed tightly upon said pin, but allowing said members to be brought into a substantially vertical position when said handle is loosened on said pin thus rendering both surfaces of the edge portions of said razor blade unobstructed for sharpening the blade without taking it off from the razor.

5. In a safety razor, the combination of a retainer cap from whose lower side extends a threaded pin adapted to be screwed into the upper extremity of a handle, with a longitudinal narrow center bar through whose perforated middle portion said pin is loosely extended, and two guard plate members hinged to the extremities of said center bar and provided with extended tongues adapted to have their extremities pressed between the upper side of said center bar and a

5

10

razor blade which is inserted beneath said retainer cap so as to keep said members in a substantially horizontal position when said handle is screwed tightly upon said pin, but allowing said members to be brought into a substantially vertical position when said handle is loosened on said pin thus rendering both surfaces of the edge portions of said razor blade accessible for sharpening without removing it from its usual position on the razor.
